BOILER CONSTRUCTION

John W. Throckmorton, Wilton, and John S. Wallis, Darien, Conn., assignors to Petro-Chem Process Company Incorporated, a corporation of Delaware

Application January 1, 1944, Serial No. 516,630

4 Claims. (Cl. 122—338)

This invention relates to improvements in boiler construction, and refers more particularly to a cylindrical or multisided upright furnace in which the source of combustion gases is located in the bottom and are discharged from a flue at the top.

The construction affords a simple, convenient, compact device for steam generation in which the boiler portion comprises a unitary assembly of a top reservoir, a lower manifold and a plurality of vertical heat exchange units which can be shop assembled and lowered as a unit into the furnace or combustion chamber.

This invention is an improvement over Letters Patent 2,334,968, issued November 23, 1943, and differs therefrom primarily in the positioning of the top reservoir in a vertical position rather than in a horizontal position transversely across the top of the furnace, and the location of the downcomer pipe centrally of the combustion space instead of outside of the furnace wall. By these changes the size of the top reservoir or drum can be made considerably smaller, reducing expense without sacrificing efficiency. The vertical position of the drum also gives better assurance of a substantial body of water as a source of supply for the water column maintained in the downcomer pipe.

The construction provides a design in which there is efficient heating of the tubes connecting the manifold with the reservoir, and a proper distribution of the heat along the heat exchange surfaces of the tubes. As the reservoir, tubes and manifold can be shop assembled as a single unit, it can be hydrostatically tested before shipment, obviating to a great extent likelihood of leakage or difficulties in establishing a pressure tight unit on the job.

The furnace is of low weight, compact and completely water-proof, so that it may be installed in the open without the necessity of a boiler house or other enclosing structure, and one which may be easily and inexpensively cleaned and repaired.

In the accompanying drawing which forms a part of the instant specification and is to be read in conjunction therewith, and in which reference numerals are used to indicate like parts in the various views,

Fig. 1 is a sectional side view of the boiler and furnace construction.

Fig. 2 is a view taken along the line 2—2, Fig. 1.

Fig. 3 is a plan view, taken from above, of the lower manifold or mud drum.

Referring to the drawing, the furnace proper comprises a cylindrical shell 10, supported by columns or standards 11. Surmounting the cylindrical shell is a flue 12 fitted with a chimney or stack 13. The flue is held in place on top of the combustion chamber or furnace by means of an angle ring 14 which not only supports the flue, but also holds and carries the weight of the vertical reservoir 15.

10 The steel shell or casing of the furnace is lined with a layer of insulation 16 and a layer of refractory firebrick 17. Extending through ports or holds in the floor of the furnace are a plurality of directional burners 18 which may be 15 adjusted to direct the combustion gases so that the heat is uniformly distributed throughout the furnace and over the surfaces of the tubes or heat exchange elements.

Although but two burners are shown, it is 20 understood that any number may be used to supply the necessary amount of heat. In place of burners it is contemplated that the combustion gases may be supplied from any type of fuel, either coal, gas or oil.

25 Below the furnace floor is supported a circular manifold or mud drum 19, which is connected to the reservoir or steam drum 15 by a plurality of heating tubes 20. These tubes are connected into the top of the manifold 19 and are 30 positioned vertically around the combustion chamber adjacent its inside wall. Their upper extremities are connected into the periphery of the steam drum at a height about midway between the top and bottom.

35 The steam drum or reservoir is equipped with a water inlet pipe which enters somewhat above its mid-portion at 21, and terminates at the bottom of the drum near the draw-off line 22 which serves as a downcomer pipe from the reservoir to the lower manifold 19.

40 Into the top of the steam drum is connected a steam outlet pipe 23, and centrally of the drum is a manhole or clean-out connection 24. At 25 in the upper part of the drum is a connection 45 for a safety valve, and at 26 is a connection to a water column.

45 In the bottom of the drum are vertical baffles 27 which prevent vortexing of the water in the location of the withdrawal through the downcomer pipe 22. At 28, in the sides of the furnace, are shown observation ports.

The downcomer pipe 22 has connections 29 with the mud drum or manifold 19, and a connection 30 with a water column, similar to that shown at 26 near the top of the steam drum. A

blowdown connection 32 and controlled by valve 33 is connected into the bottom of the water column 22.

In the upper portion of the combustion chamber or furnace is arranged a baffle which has an upper cylindrical portion 31, and a lower conical portion 31a. The apex of the depending cone 31a is truncated and open to permit passage of the downcomer pipe 22 therethrough.

From the construction the operation of the boiler is obvious. Combustion gases produced by the burning of fuel in burners 18 pass upwardly through the cylindrical furnace and are diverted outwardly by the conical portion 31a of the baffle. In the lower portion of the furnace the heating tubes 20 are subjected principally to radiant heat, and it is in this zone that a major portion of the heat exchange between the combustion gases and water passing through the tubes is effected.

Cone 31a causes the gases to be diverted outwardly into the annular space formed between the cylindrical portion 31 of the baffle and the inside wall of the furnace. The heating tubes 20 extend through this annular passageway and in this portion of the furnace the heat exchange elements or tubes are equipped with extended surface in the form of radial fins 20a which extend longitudinally of the tubes and are welded to the tubes to produce efficient heat exchange between the convection heat of the gases and the fluid passing through the tubes. As this annular passageway receives primarily only convection heat, the efficiency of the tubes is considerably augmented by the extended surface. Above the passageway the tubes are shaped inwardly and connected to the steam drum near its mid-section. The combustion gases after passing through the annular space, between the baffle and furnace wall, pass upwardly through flue 12 over the sides of the steam drum and out through chimney 13.

The water to be heated in the boiler and from which steam is to be generated is supplied through inlet pipe 21 by means of which it is delivered into the bottom of the reservoir in the throat of the downcomer pipe 22. Its course is downwardly through the downcomer pipe, thence through connections 29 into the mud drum or lower manifold 19, where it is distributed to the vertical tubes 20. Rising through these tubes, the water is heated by the combustion gases and is discharged into the steam drum where unvaporized liquid returns to the downcomer pipe while the steam is drawn off through outlet 23. Liquid discharged into the upper reservoir through heating tubes 20 is prevented from swirling or vortexing about the downcomer pipe by means of baffles 27.

The downcomer pipe being located within the baffle for a considerable part of its length is subjected to somewhat lower temperatures than the heating tubes arranged about the surface wall of the furnace, thereby assuring relatively rapid circulation due to convection currents in the system. In other words, that portion of the downcomer protected by the baffle receives considerably less heat than the heating tubes in the upper portion of the combustion chamber; likewise that portion of the downcomer below the baffle being located centrally of the furnace and having comparatively less exposed surface than the columns of water in the heating tubes transmits less heat to the fluid passing therethrough. Furthermore, the directional burners are ar-

ranged to project the combustion gases outwardly against the heating tubes, where the highest temperatures are concentrated.

Thus it will be seen that relatively rapid convection currents will be created in the system due to the severe heating of the bank of tubes surrounding the combustion space where the rising fluid flows, the more moderate heating of the column of liquid in the downcomer and the maintenance of a liquid body in the steam drum protected from extreme heat by the baffle and supplying the coolest liquid in the boiler to the down-flowing column in the downcomer.

As many possible embodiments may be made of the invention without departing from the scope thereof it is understood that all matter herein set forth or shown in the drawing is to be interpreted as illustrative, and not in a limiting sense.

From the foregoing it will be seen that our invention is one well adapted to attain all of the ends and objects, together with other advantages which are obvious and which are inherent to the structure.

Having thus described our invention, we claim:

1. A boiler construction comprising a vertical chamber having a source of combustion gases in the lower portion thereof, a flue at the top, a baffle intermediate the flue and combustion gas source causing outward divergence of the gases leaving the chamber, a cylindrical reservoir vertically positioned in the upper part of the chamber above the baffle, a lower manifold adjacent the bottom of the chamber, heat exchange elements surrounding the chamber and adjacent its inside wall surface connecting the manifold and reservoir, a downcomer positioned centrally of the chamber connecting the reservoir and lower manifold, a fluid inlet to the reservoir, and a vapor outlet therefrom.

2. A boiler construction comprising a vertical chamber having a source of combustion gases in the lower portion thereof, a flue at the top, a baffle intermediate the flue and combustion gas source causing outward divergence of the gases leaving the chamber, a cylindrical reservoir vertically positioned in the upper part of the chamber above the baffle, a lower manifold adjacent the bottom of the chamber, heat exchange elements surrounding the chamber and adjacent its inside wall surface connecting the manifold and reservoir, extended surfaces on the heat exchange elements in that portion of the chamber wherein the path of the combustion gas is outwardly diverged by the baffle, a downcomer positioned centrally of the chamber connecting the reservoir and lower manifold, a fluid inlet to the reservoir, and a vapor outlet therefrom.

3. A boiler construction comprising a vertical cylindrical chamber having a source of combustion gas in the lower portion thereof, a flue at the top, a cylindrical baffle having a lower end in the form of a depending cone intermediate the flue and combustion gas source, said baffle forming an annular space with the wall of the chamber in its upper portion, a cylindrical reservoir vertically positioned in the upper part of the chamber above the baffle, a lower manifold adjacent the bottom of the chamber, heat exchange elements surrounding the chamber and adjacent its inside wall connected to the manifold at their lower extremities and having their upper portions located in the annular space surrounding the baffle and connected to the periphery of the reservoir at their upper extremities, a downcomer positioned centrally of the chamber connecting

the reservoir and lower manifold, a fluid inlet to the reservoir, and a vapor outlet therefrom.

4. A boiler construction comprising a vertical chamber having a source of combustion gases in the lower portion thereof, a flue at the top, a baffle intermediate the flue and combustion gas source causing outward divergence of the gases leaving the chamber, a cylindrical reservoir vertically positioned and located partially in the upper portion of the chamber and partially in the 10

lower portion of the flue, a lower manifold adjacent the bottom of the chamber, heat exchange elements surrounding the chamber and adjacent its inside wall surface connecting the manifold and reservoir, a downcomer positioned centrally of the chamber connecting the reservoir and lower manifold, a fluid inlet to the reservoir, and a vapor outlet therefrom.
